J. A. DANDRIDGE, OF BUFFALO, NEW YORK.

Letters Patent No. 95,202, dated September 28, 1869.

IMPROVED BURIAL-CASE.

The Schedule referred to in these Letters Patent and making part of the same.

To all whom it may concern:

Be it known that I, J. A. DANDRIDGE, of Buffalo, in the county of Erie, and State of New York, have invented a new and useful Improvement in Burial-Cases; and I do hereby declare that the following is a full, clear, and exact description thereof, which will enable others skilled in the art to make and use the same.

This invention relates to improvements in burial-cases, the object of which is to provide highly ornamental cases by a more simple and inexpensive process than the present modes of constructing them.

Figure 1 represents a top view of my improved burial-case, with the ornamentation, hereinafter described, upon its cover.

Figure 2 is a transverse sectional view of the said cover.

My process consists in taking a metallic plate and producing on one surface thereof any desired orna-

tation, affixing a thin sheet or layer of adhesive substance on the top of the cover, and then uniting the three materials together by pressure under a dry heat.

By this process I form a "casé" for burial or analogous purposes; which combines any degree or quality of ornamentation, with great durability, and economy in the cost of production.

I have no design to claim as of my invention electro-plating or any particular method of ornamentation; but

What I do claim, and desire to secure by Letters Patent, is—

As an article of manufacture, a burial-case of wood, electro-plated and ornamented, as set forth in specification.

J. A. DANDRIDGE.
